S. D. WALDON,
HYDROCARBON MOTOR,
APPLICATION FILED FEB. 16, 1916.

1,323,508.

Patented Dec. 2, 1919.

UNITED STATES PATENT OFFICE.

SIDNEY D. WALDON, OF DETROIT, MICHIGAN, ASSIGNOR TO CADILLAC MOTOR CAR COMPANY, OF DETROIT, MICHIGAN, A CORPORATION OF MICHIGAN.

HYDROCARBON-MOTOR.

1,323,508.

Specification of Letters Patent.

Patented Dec. 2, 1919.

Application filed February 18, 1916. Serial No. 78,609.

To all whom it may concern:

Be it known that I, SIDNEY D. WALDON, a citizen of the United States, and resident of Detroit, Wayne county, State of Michigan, have invented certain new and useful improvements in Hydrocarbon-Motors, of which the following is a specification.

This invention relates to hydrocarbon motors, and particularly to circulating systems, which may be easily applied thereto.

One of the salient objects of this invention is to provide a simple and efficient means for controlling the circulating medium in a liquid system, particularly of the forced circulation type without setting up objectionable back pressures when the circulation is retarded.

Another object is to provide a forced circulating cooling system, such as used in a hydrocarbon motor, with means for positively and effectively stopping the entire circulation of the cooling medium, without encountering the objectionable features which have resulted with the use of previously known systems.

Another object is to provide a liquid cooling system comprising a pump, the usual jacket, radiator and connections, with a shunt circuit around the pump, the circulation through which is adapted to be controlled by a valve mechanism.

Another object is to provide a valve mechanism in the connections between the jacket, radiator and pump, and adapted to be actuated by the temperature of the liquid in the jacket.

These, and other objects, will appear from the following description, taken in connection with the accompanying drawings, which form a part of this specification, and in which:

Figure 1 is a side elevation, with portions broken away, of a power plant, embodying a preferred form of my invention;

Fig. 2 is a transverse vertical section, substantially on the line 2—2 of Fig. 1; and

Fig. 3 is a horizontal section, substantially on the line 3—3 of Fig. 2.

Referring to the drawings, 10 represents the usual crank case of a hydrocarbon motor, on which may be mounted, in suitable V or other relation, a plurality of cylinder blocks, one of which is illustrated at 11. The usual radiator 12 and fan 13 are arranged at the front end of the motor.

The cylinder block is provided with the usual liquid jacket 14, having an intake port 15 and outlet or discharge port 16. A flexible conduit 17 connects the outlet port 16 with the upper part of the radiator, as at 18, 60 and the lower part of the radiator, as at 19, may be connected as by a similar conduit 20, to an intake port 21 formed in the casing 22 of a pump mechanism, which will be more particularly described hereinafter. 65 Another conduit 23 connects a discharge port 24 of the pump casing with the jacket intake port 15.

The well known crank shaft 25 is illustrated, particularly in Fig. 2, as suitably 70 mounted in the crank case 10, and is provided with a spiral gear 26, which is adapted to drive a similar gear 27 on a pump shaft 28. This shaft is arranged below the crank shaft, transversely thereto, in suitable plain 75 bearings 29 in the crank case, and another bearing 30 in the pump casing 22. A pump impeller, of the well known turbine type, is shown at 31, as mounted on the shaft 28 and secured thereon, as by a pin 32. 80

The pump casing 22, which is adapted to be mounted on the crank case, as by bolts 33, has its intake port 21 leading into an interiorly arranged shell 35, shown as formed integral with the casing. This shell has ports 85 36 and 37 formed in its upper and lower portions, respectively, leading to the interior of the pump casing. A channel 38 is also formed in the casing 22 and forms a shunt circuit between the discharge port 24 of 90 the casing and the suction chamber 39 through a port 40, which is formed in a wall 41 between the suction chamber and the channel 38.

The circulation of the cooling medium is 95 adapted to be controlled by a valve mechanism consisting of a rod 42 having a valve member 43 arranged thereon, shown as formed integral therewith, for controlling the circulation through the port 40. Another 100 double balanced valve member 44 is arranged on the end of the rod 42 and secured in position by means of a taper pin 45, which may be screwed on to the threaded portion 46 of the rod. The latter valve 105 member is adapted to control the circulation through the ports 21, 36 and 37.

It will be noted that the upper part of the valve rod 42 extends through the cover 47 of the valve casing to a point within a thermo- 110

stat chamber 48, which is secured, as by bolts 49, to the cylinder jacket 14; and a thermostat 50, whose upper end is adapted to be threaded, as at 51, to the chamber 48, 5 has its lower end secured to the valve rod 42, which is actuated thereby. A flexible tube 52 houses the valve rod and a sufficient clearance is provided between the exterior of the rod and its chamber, as at 53, to permit a 10 small quantity of the cooling liquid to circulate from the thermostat chamber down into the pump chamber, thereby preventing the formation of a dead pocket of liquid in the thermostat chamber.

15 Having thus described the general construction and arrangement of parts, the operation of the cooling system will be understood as follows: Assuming the motor to be started up when the temperature of the 20 cooling medium is below the desired heat, the thermostat will be contracted sufficiently to seat the valve member 44 on the ports 36 and 37, thus preventing the circulation of liquid through the intake port 21 from the 25 radiator 12, and the valve member 43 will also be lifted from the port 40 into substantially the position shown in Fig. 2; therefore any liquid which is drawn from the suction chamber 39 by the impeller 31 will 30 be returned to it through the channel 38 and port 40. Consequently there will be no circulation through the cylinder jacket 15, except for the small quantity of liquid which will be held down through the clearance 35 between the valve rod and its housing 52, and under these conditions there will not be any circulation in conduits 17 and 20 and the radiator 12.

However, when the temperature in the 40 jacket rises above the desired heat, the thermostat will expand, pushing the valve member 43 toward the port 40, thus retarding the circulation therethrough, and dropping the valve member 44 from the ports 36 and 37, 45 increasing the circulation through these ports and intake port 21 until the full action of the pump is exerted in forcing the liquid from the discharge port 24 through the jacket intake conduit 23, jacket intake port 50 15, thence through the jacket and discharged therefrom at outlet port 16 and through the connecting conduit 17, radiator 12, connecting conduit 20 and intake port 21 to the pump impeller.

55 It will thus be understood that while I have provided means for entirely stopping the circulation through the jackets, no back pressure is set up by the pump as its circulation is left unimpeded at all times.

60 It will also be noted, that while I have arranged my valve mechanism on the suction side of the pump, it is adapted to be actuated by a thermostat arranged where it will be sensitive to the temperature of the liquid 65 within the cylinder jacket.

While I have described and will specifically claim what I deem to be a preferred embodiment of my invention, it will be understood that various modifications and changes may be made, by one skilled in the 70 art, without departing from the spirit and scope hereof.

Having thus described my invention, what I claim and desire to secure by Letters Patent is:

1. In a hydrocarbon motor, the combination with a cylinder block, a jacket therefor, provided with an intake port and a discharge port, a pump mechanism therefor having an intake port and a discharge port, 80 connections between said pump and jacket for providing a circulating system, and means for connecting said pump discharge port with its intake port independently of said jacket.

2. In a hydrocarbon motor, the combination with a cylinder block, a jacket therefor, provided with an intake port and a discharge port, a pump mechanism therefor having an intake port and a discharge port, 90 connections between said pump and jacket for providing a circulating system, and means for connecting said pump discharge port with its intake port independently of said connections.

3. In a hydrocarbon motor, the combination with a cylinder block, a jacket therefor, provided with an intake port and a discharge port, a pump mechanism having similar ports; a conduit from said pump 100 discharge port to said jacket intake, a conduit connection from said jacket discharge port to said pump intake, a valve mechanism in said connection, and means comprising a valve for connecting said pump 105 ports independent of said conduits.

4. In a hydrocarbon motor, the combination with a cylinder block, a jacket therefor provided with an intake port and a discharge port, a pump mechanism having 110 similar ports, a conduit from said pump discharge port to said jacket intake, a conduit from said jacket discharge port to said pump intake, a valve mechanism for said pump intake port, means comprising a 115 valve for connecting said pump ports independent of said conduits, and common thermostatically actuated means for controlling said valves.

5. In a hydrocarbon motor, the combination with a cylinder block, a jacket therefor provided with an intake port and a discharge port, a pump mechanism having similar ports, a conduit from said pump discharge port to said jacket intake, a conduit from said jacket discharge port to said pump intake, a valve mechanism for said pump intake port, means comprising a valve for connecting said pump ports independent of said conduits, and a thermostat ac- 120 125 130

tuated by the temperature within said jacket for controlling said valves.

6. In a hydrocarbon motor, the combination with a cylinder jacket, a radiator, a 5 pump, and connecting conduits whereby a cooling liquid may be circulated through said jacket and radiator by said pump; valve mechanism for controlling the flow of cooling liquid through said jacket and radiator; a thermostat exposed to the said cooling liquid and adapted to control said valve mechanism; and a leak passage of restricted area independent of said radiator, and through which cooling liquid may flow 10 from said jacket to the inlet side of said pump without passing through said radiator.

7. In a hydrocarbon motor, the combination with a cylinder jacket, a radiator, a 20 pump, and connecting conduits whereby a cooling liquid may be circulated through said jacket and radiator by said pump; valve mechanism for controlling the flow of cooling liquid through said jacket and radiator; a thermostat operatively connected 25 with said valve mechanism to operate the

same, and which thermostat is exposed to said cooling liquid at the point where said liquid is at its highest temperature; and a leak passage of restricted area and through 30 which cooling liquid may flow from said jacket to the inlet side of said pump without flowing through said radiator.

8. In a hydrocarbon motor, the combination with a cylinder jacket, a radiator, a 35 pump, and connecting conduits whereby a cooling liquid may be circulated through said jacket and radiator by said pump; valve mechanism for controlling the flow of cooling liquid through said jacket and 40 radiator; a chamber secured to and communicating directly with the interior of said water jacket; a thermostat located within said chamber and adapted to control said valve mechanism; and a leak passage 45 leading from said chamber to the inlet side of said pump and through which liquid may flow from said jacket to said pump without passing through said radiator.

In testimony whereof I affix my signature.

SIDNEY D. WALDON.
